SAW BLADE HOLDING ATTACHMENT FOR
PLIERS

Burton Patridge Johnston, Los Angeles, Calif.

Application July 10, 1946, Serial No. 682,717

4 Claims. (CL. 81—52)

1

This invention relates to a novel tool in the form of a clamp adapted to be used in combination with a conventional pair of pliers for detachably supporting a hacksaw blade for executing a conventional operation with the blade.

More particularly, it is an aim of the invention to provide a blade holder or clamp of extremely simple construction and which is capable of being conveniently used for supporting a hacksaw blade for executing a cutting operation in an inaccessible location where a conventional hacksaw frame could not be accommodated.

Still a further object of the invention is to provide a holder or clamp which is so constructed and arranged that blades of different widths may be mounted therein and be positioned on either side of a pair of pliers, engaging the clamp, and with the teeth of the clamped hacksaw blade facing either upwardly or downwardly for thereby accommodating the tool for operation in inaccessible places where other saws could not be employed.

Still a further object of the invention is to provide a blade holder or clamp possessing the above described characteristics, and which is capable of being economically manufactured and sold, and which will be extremely durable and efficient in operation for its intended function.

Various other objects and advantages of the invention will hereinafter become more fully apparent from the following description of the drawing, which illustrates a preferred embodiment thereof and wherein:

Figure 1 is a side elevational view, showing the clamp in an operative position engaged in the jaws of a pair of pliers and engaging an end of a conventional hacksaw blade;

Figure 2 is a top plan view thereof;

Figure 3 is an end view in elevation thereof, taken in a transverse plane through the saw blade as indicated by the line 3—3 of Figure 1;

Figure 4 is an enlarged perspective view of the blade holder or clamp;

Figure 5 is a longitudinal sectional view taken substantially along a plane as indicated by the line 5—5 of Figure 2, and

Figure 6 is a perspective view, on an enlarged scale, of the blank from which the holder or clamp is formed.

Referring more specifically to the drawing, the blade holder or clamp in its entirety is designated generally 7 and to illustrate the adaptation and use thereof, a conventional pair of pliers is shown and designated generally 8 and a portion of a conventional hacksaw blade is indicated at 55

2

9. The pliers 8 and blade 9 form no part of the present invention, but as they are utilized in conjunction therewith, these parts have been illustrated in the drawing to better disclose the application and use of the holder or clamp 7.

The holder or clamp 7 is formed from a single blank of tempered steel, as indicated in Figure 6, and is stamped, pressed and bent into the shape as seen in Figure 4 to form the holder. As best illustrated in Figure 4, the corresponding end portions 10 of the blank of Figure 6, are disposed in superimposed, spaced apart relationship to form jaws 11 and 12. The intermediate connecting portion 13 of the blank of Figure 6 is bent to form a loop portion 14 which connects the jaws 11 and 12 and which is disposed beyond the inner ends thereof.

The jaws 11 and 12 are provided, adjacent corresponding longitudinal edges thereof, with 20 outwardly pressed portions forming relatively shallow inwardly opening opposed channels or grooves 15 and 16, respectively. The opposite side edges of the jaws 11 and 12 are likewise pressed outwardly to form opposed inwardly 25 opening channels or grooves 17 and 18, respectively, which are substantially deeper than the grooves 15 and 16, and which are likewise disposed in inwardly opening, opposed relationship. The intermediate, loop portion 14 is provided 30 with wings or extensions 19 which may be utilized in positioning the loop portion 14 between the jaws 20 of the pliers 8.

As best illustrated in Figure 1, the jaws 20 of the pliers 8 are of conventional shape having concave, opposed serrated faces between which the loop portion 14 is adapted to be disposed, and it will be readily apparent from a consideration 35 of Figure 1, that the intermediate, arcuate part of the loop portion 14 is contoured to substantially conform to the curvature of the serrated faces of the jaws 20, so as to fit snugly therebetween and to be effectively engaged thereby. An end of the hacksaw blade 9, which may be a broken blade, no longer capable of use in a hacksaw frame, is adapted to be positioned with its toothed edge in one of the channels 15, 16, 17 or 18 and with its back edge in the channel, disposed in opposed relationship thereto, so that 45 when a pressure is exerted on the handle end of the pliers 8, the jaws 20 will be moved toward closed positions to compress the loop portion 14 to thereby move the jaws 11 and 12 toward one another for clamping said end of the blade 9 in the channels or grooves, engaged thereby. It will 50

be readily apparent that the toothed edge of the blade 9 will effectively cooperate with the channel or groove in which it is received to prevent displacement of the blade while thus held by the clamp 7, which is in turn engaged by the pliers 8, so that the user by grasping the pliers handles may execute a sawing operation with the blades 9 in inaccessible locations, where a hacksaw frame could not be accommodated. It will likewise be readily apparent that the blade 9 could be inverted from its position of Figures 1 and 2, so that the toothed edge thereof would face upwardly and be disposed in the groove 18 instead of in the groove or channel 17, as illustrated. Likewise, it will be readily obvious that the clamp 7 could be rotated a half-turn on its longitudinal axis and positioned in the pliers 8 for positioning the clamping grooves 17 and 18 on the other side of the pliers 8 for mounting the saw blade 9 on the opposite side of the pliers to its position as illustrated in Figures 1, 2 and 3.

Grooves 15 and 16 are made shallower so that the distance between the beds of the grooves 15 and 16 will be less than the distance between the beds of the grooves 17 and 18 for accommodating saw blades in said first mentioned grooves which are narrower than the saw blade 9, thus adapting the holder or clamp 7 for use with saw blades of at least two widths. Likewise, it will be readily apparent that the size of the holder 7 and the depth of the grooves thereof may be varied for use with saw blades of hacksaws of any standard size.

Various other modifications and changes are likewise contemplated and may obviously be resorted to without departing from the spirit and scope of the invention as hereinafter defined by the appended claims.

I claim:

1. In a blade holder or clamp, a pair of opposed, spaced jaws provided with opposed, channel portions or grooves which are offset from the planes of the jaws in directions away from one another and which open toward one another for accommodating the longitudinal edges of a hacksaw blade in said grooves or channel portions, and a loop portion, having ends connected to the inner ends of said jaws for supporting said jaws in

normally spaced apart relationship, said loop portion being adapted to be engaged and clamped between the jaws of a pair of pliers and the blade holding jaws being engaged by the plier jaws for moving said blade holder jaws toward one another and into clamping engagement with the hacksaw blade when said loop portion is compressed by closing movement of the pliers' jaws.

2. A blade holder or clamp as in claim 1, said grooves or channel portions being disposed adjacent the side edges and longitudinally of the clamp jaws whereby said clamp may be inverted with respect to the jaws of the pliers for positioning the saw blade on either side of the pliers' jaws.

3. In a blade holder or clamp, a pair of spaced jaws provided with outwardly offset inwardly opening grooves adapted to engage the edge portions of an end of a hacksaw blade, and a resilient

loop portion having end portions connected to corresponding ends of said jaws for resiliently supporting the jaws relatively to one another, said jaws having longitudinally extending flat surfaces disposed on corresponding sides of the grooves adapted to be engaged between the jaws of a pair of pliers, forming a handle for the blade holder, said pliers' jaws being movable toward closed positions for moving the blade holder jaws into clamping engagement with the edge portions of the hacksaw blade.

4. A blade holder or clamp as in claim 1, said blade holder jaws each comprising a plate having an outwardly projecting longitudinally extending portion forming said inwardly opening channel or groove.

BURTON PATRIDGE JOHNSTON.
